UNITED STATES PATENT OFFICE.

MICHAEL MUTRO, OF CHESTER, PENNSYLVANIA.

PROJECTILE FOR FIELD-GUNS.

1,272,984.

Specification of Letters Patent. Patented July 16, 1918.

Application filed February 5, 1917. Serial No. 146,675.

To all whom it may concern:

Be it known that I, MICHAEL MUTRO, subject of the Emperor of Austria, residing at Chester, in the county of Delaware and State of Pennsylvania, have invented certain new and useful Improvements in Projectiles for Field-Guns, of which the following is a specification.

This invention relates to projectiles and has special reference to a projectile for field guns.

One important object of the invention is to provide an improved form of explosive projectile arranged to explode over several successive areas of ground occupied by troops and thereby work damage to the troops in different trenches.

It is well understood that the range, under conditions of modern warfare, is often difficult to ascertain with accuracy.

Another important object of the invention is to provide a projectile different sections of which will explode in succession so that the oval space covered by the fragments and shrapnel of an ordinary projectile will be greatly lengthened so that ordinary variations from the true range will not affect the damaging power of the projectile.

A third important object of the invention is the provision of an improved form of projectile having successive explosion stages by means of which there will be produced a primary backward shower of fragments and shrapnel and a final forward and lateral shower of fragments and shrapnel.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:

Figure 1 is a longitudinal median section through a projectile constructed in accordance with this invention.

Fig. 2 is a section on the line 2—2 of Fig. 1.

Fig. 3 is a section on the line 3—3 of Fig. 1.

In the embodiment of the invention herein illustrated there is disclosed a projectile having a forward portion 10 terminating in a nose 11 at one end and in a reduced por-

tion 12 at its other end. On the rear end of the body 10 is secured a rear body 13 as by the threads 14. This rear body is substantially cylindrical in form and its rear end is internally rabbeted and provided with fine pitched screw threads 15 to receive the threaded portion of a plug 16 having an outwardly extending flange 17 resting against the butt of the projectile. Screwed centrally in this plug is a fuse plug 18 having a slow inwardly burning fuse 19 running therethrough which is bifurcated internally of the projectile and secured to cups 20 holding fulminate of mercury.

Intermediate the ends of the rear body 13 there is provided a substantial partition 21 through which extend the branches of the fuse 19. The space between the base plug 16 and partition 21 is filled with powder as shown at 22.

Now, when the projectile is fired the flame of the discharge will light the fuse 19 and this will communicate the necessary fire to the fulminate and thus to the powder 22, the time taken to fire this powder being dependent on the rate of burning of the fuse 19. The effect of the explosion of this charge of powder will be to throw the plug 16 backward, and usually in fragments, the plug readily separating from the body 11 because of the weakness of the fine threads 15. Thus, if the projectile overshoots a body of troops they will receive the discharge from its rear end.

Spaced in front of the partition 21 is a partition 23' and between these two partitions and resting on the partition 21 is a casing 23 filled with shrapnel 24. Through this casing extend the branches of the fuse 19, these branches terminating in fulminate of mercury primers 25 arranged to fire a charge of powder 26 between the two partitions and a charge 27 located between the partition 23' and a strong partition 28 fixed firmly in the body 10. Moreover there is embedded in the center of the charge 26 a charge 29 of high explosive, such as guncotton.

When this secondary explosion takes place the effect will be, owing to the charge of guncotton, to disrupt the walls of the rear body 11 and blow them and the shrapnel laterally but the explosion of the charge 27 will also blow the wall fragments and shrapnel rearwardly.

Forward of the partition 28 is located a

central powder chamber 30 filled with powder 31 arranged to be fired by a percussion fuse typified by the construction shown at 32. Surrounding this chamber 30 and filling the space between the chamber and body wall is shrapnel 33.

When the projectile strikes a resisting object, usually after the first explosions above referred to the percussion fuse sets off the charge 31 with the resultant disruption of the walls of the body and the scattering broadcast of these walls and the shrapnel 33.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, what is claimed as new, is:—

1. An explosive projectile consisting of front and rear hollow bodies connected together at adjacent ends, a plug closing the rear end of the rear body and readily detachable rearwardly therefrom, a powder charge resting against said plug, a partition intermediate the ends of the rear body, an annulus of shrapnel forward of said partition in the rear body, an explosive charge

filling the space forward of the partition in the rear body left by said shrapnel, said explosive charge having a core of guncotton, a partition between the ends of the front body, an explosive charge in the rear end of the front body, and means to fire the first charge and, thereafter fire the second and third charge.

2. An explosive projectile consisting of front and rear hollow bodies connected together at adjacent ends, a plug closing the rear end of the rear body and readily detachable rearwardly therefrom, a powder charge resting against said plug, a partition intermediate the ends of the rear body, an annulus of shrapnel forward of said partition in the rear body, an explosive charge filling the space forward of the partition in the rear body left by said shrapnel, a partition between the ends of the front body, an explosive charge in the rear end of the front body, means to fire the first charge and thereafter fire the second and third charge, an explosive charge in front of the partition in the front body, impact actuated means for firing the last-mentioned explosive charge, said first-mentioned explosive charge having a core of guncotton.

In testimony whereof I affix my signature in the presence of two witnesses.

MICHAEL MUTRO.
